UNITED STATES PATENT OFFICE.

THOMAS W. RIEDER, OF PITTSBURG, PENNSYLVANIA.

WHEEL FOR VEHICLES.

No. 878,564.

Specification of Letters Patent.

Patented Feb. 11, 1903.

Application filed February 28, 1907. Serial No. 359,841.

To all whom it may concern:

Be it known that I, THOMAS W. RIEDER, a citizen of the United States of America, residing at Pittsburg, in the county of Allegheny and State of Pennsylvania, have invented certain new and useful Improvements in Wheels for Vehicles, of which the following is a specification, reference being had therein to the accompanying drawing.

10 This invention relates to wheels for vehicles, and the invention has for its object to provide a novel wheel, which will thoroughly cushion a vehicle and relieve the occupants thereof of any jarring or disagreeable sensations when traveling over rough and irregular surfaces.

Another object of this invention is to provide a simple and inexpensive wheel that can be used in connection with vehicles where- 20 in the ordinary elliptical body supporting springs are dispensed with.

With the above and other objects in view, which will more readily appear as the invention is better understood, the same consists 25 in the novel construction, combination and arrangement of parts to be hereinafter more fully described and then, specifically pointed out in the appended claims, and referring to the drawing forming part of this specification, 30 like numerals of reference designate corresponding parts throughout the several views, in which:-

Figure 1 is an elevation of my improved wheel, Fig. 2 is an enlarged detail sectional view taken on the line $z-z$ of Fig. 1, Fig. 3 is a perspective view of one of the spring fastening plates used in connection with the wheel.

To put my invention into practice, I construct my improved wheel of a hub 1 of a 40 conventional form having radially projecting spokes 2 carrying an inner rim 3, the periphery of which is covered by a metallic band or plate 4. To the band or plate 4 is secured a plurality of spring fastening plates 5, bolts 45 and nuts 6 being preferably used for this purpose. The spring fastening plates are formed between their ends with sleeves 7 adapted to receive pins 8 for pivotally connecting springs 9 to the inner rim 3 of the wheel. The springs 50 9 are of coiled form, and are provided at each end with eyes disposed at opposite sides of the spring. The eyes 10 at each end of the spring are formed by simply looping or bending the last convolution of the coil, and the 55 eyes 12 are formed by looping the free ends of the wire from which the spring is formed, these

ends 11 being then hooked into engagement with one of the convolutions of the coil as clearly seen in Fig. 2. Thus, each spring has an eye 10 and an eye 12 at each end thereof, 60 the eye 10 of one end of the spring being on the opposite side thereof to the eye 10 at the opposite end of the spring and similarly, the eye 12 at one end of the spring being at the opposite side thereof to the eye 12 at the other 65 end of the spring. The eyes 10 and 12 at the inner end of each spring receive the pins 8 carried by the sleeve 7, and the eyes 10 and 12 at the outer ends of the springs receive similar pins carried by plates 14 of the same 70 construction as the plates 5, and similarly secured to the felly 15, which latter is provided with a solid resilient tire 16.

It will be apparent from the illustration of my invention that I have devised a wheel of 75 considerable strength and durability having radially disposed spokes alternately arranged with respect to the radially disposed springs, these springs being of sufficient tension and rigidity to firmly support the felly and tire 80 of the wheel. A particular feature of my invention resides in the novel manner in which the springs are trunnioned to the inner rim and the outer rim or felly of the wheel, this novel connection permitting of the free 85 movement of the springs in perfectly cushioning the body of a vehicle upon the wheels.

I do not care to confine myself to the type of wheel in connection with which the springs are used, or to the number of springs used 90 with one wheel.

Such changes in the details of construction as are permissible by the appended claims, may be resorted to without departing from the spirit and scope of the invention.

What I claim and desire to secure by Letters Patent, is:-

1. A vehicle wheel consisting of a hub, radially disposed spokes carried thereby, an inner rim carried by said spokes, a felly surrounding said rim, spring fastening plates connecting with said felly and said rim, pins loosely mounted in said plates, coiled springs interposed between said plates, and having their two end convolutions bent to 100 form eyelets to engage the ends of said pins upon each side of said wheel.

2. In a spring wheel, the combination of a rim, plates secured to said rim and each provided between its ends with a sleeve, a felly 110 surrounding said rim, plates secured to the inner face of said felly, each provided be-

tween its ends with a sleeve, pins mounted in the sleeves of said plates on the rim and pins mounted in said plates on the felly, and coiled springs interposed between the plates on the rim and the plates on the felly, each spring formed at each end with a pair of oppositely disposed eyes to receive respectively the pins carried by the plates on the

rim and the plates on the felly and secure said springs in position.

In testimony whereof I affix my signature in the presence of two witnesses.

THOMAS W. RIEDER.
